UNITED STATES PATENT OFFICE.

RUBY T. BREWSTER, OF NEW YORK, N. Y.

DESIGN FOR A CLOSURE FOR RECEPTACLES FOR PERFUMERY PRODUCTS.

Application filed October 29, 1927. Serial No. 23,921. Term of patent 3½ years.

To all whom it may concern:

Be it known that I, RUBY T. BREWSTER, a citizen of the United States, residing at New York city, in the county and State of New York, have invented a new, original, and ornamental Design for a Closure for Receptacles for Perfumery Products, of which the following is a specification, reference being had to the accompanying drawing, forming part thereof.

I claim:

The ornamental design for a closure for receptacles for perfumery products, as shown.

RUBY T. BREWSTER.
